George B. Howland
Inventor

By his Attorney
Frank D. Thomason

nishes the actuating power. It is constructed
in a simple and comparatively-inexpensive
manner, and is less possible of adjustment
consistent with proper operation, and is always
under complete control, substantially as herein-
inafter fully described, and as illustrated in
the drawings, which are as follows:

Figure 1 is a side elevation of my invention,
showing the right-hand end portion there-
of, including a detail view, Fig. 2, of an
end elevation thereof, showing parts of
the cross-bar of the head-frame of the case
broken away. Fig. 3 is a transverse vertical
central section of the case, and Fig. 4 is a
detail view of the bearings of the meter.

Reference being had to the drawings, A repre-
sents a grain-feeding and oscillating case, which is
provided with an inlet pipe or opening *a* en-
tering its top at about its center of length,
and is provided with an outlet-opening *b*, lat-
erally, on the side of its lower edge, corresponding
to about that of the meter inclosed within
the case, and of a width equal to about twice
the extent of its oscillation. The ends of the
case are secured, by and are secured to
head-frames *B*, which are cast in one piece
and are bolted to the frame *C*, which is
a little above the center of height of said
frames, and these cross-bars have projecting
hinged from their lower edges, cross-bars
hanging at the centers of length of which I
prefer to make the bearings for the oscillat-
ing meter *D*, as shown in Fig. 4. These bearing
are formed of two wood-rodings, *c*, *c*, and
shaped bearings *c*, *c*, placed about an inch
apart, upon first one and then the other of

greater in diameter, and its sides *D'*, con-
necting the ends of this lowest segment there-
of, are flat, and the sides, having the greater di-
ameter, are flat. The meter *D* is divided
longitudinally into two equal measuring com-
partments *e* and *e'*, by a vertical partition
E, commencing at a point intersecting
the center of the lowest segment of the meter
D, passes diametrically and vertically through
the same, in the upper portion of each
compartment, preferably alongside of partition
E, are inlet-openings *f*, *f*, which are of a
certain little greater than the diameter of
oscillation of the meter, and are of a length
a little greater than that of opening *a* of the
case, and each of the compartments *e* and
e' is provided with an outlet *f*, *f*, in the flat sides
of the meter *D*. In order to facilitate the
escape of the grain when either outlet is open,
the lower edge of the partition *E* is inclined at
an angle, whose outer surface are inclined at
a suitable pitch from the partition to the ad-
jacent longitudinal edge, so that the inlet *f* of
first compartment *e*, and then of compartment
e', will come directly under the inlet *a* of the
case.

The principal feature of my invention is
the automatic closing of the outlet *f* of the
compartment whose inlet *a* is under inlet
a of the case, and the automatic opening of
the outlet *f* of the compartment whose inlet
a is not under inlet *a* of the case. This I easily
accomplish by providing stop-walls *G*,
which are placed in front of inlet *D'* (in which
is made the outlet of the compartment whose
inlet is under the inlet *a* of the case) strikes
inlet *a* so as to effectually close the outlet
f therewith. These walls *G* are placed a cor-
responding distance from the vertical plane
intersecting the center of oscillation of the

horizontal range on the cross-bar, and have a 95
threaded end. The lower end is threaded and
30 by turning these nuts the springs g are tightened
or loosened, so as to require greater or
less pressure to be applied to the free end of
the lever g to oscillate the meter. The spring
secured to or made integral with the stand- 100
ards just above the horizontal plane of levers
 g is free, except during its upward movement.
Ward beyond a horizontal position, no matter
how tight the springs g^2 may be made. Five
35 seconds to the end of the meter next
said lever g at a distance from the center of the
oscillating meter D which is slightly greater
than the free end of the lever therefrom,
are the oscillating catches K . When
40 the meter oscillates, the catches K strike the
side that is moving upward, strikes against the
end of the lever g on that side, and is swung
upward therewith until past the same, where-
upon it oscillates back to its original position
45 and catches upon the end of the lever just
upon the time said meter reaches the limit
of its oscillation, and vice versa. When the
uppermost compartment of the meter, the
50 pressure on lever g is so great as to cause it
to oscillate, one of the two levers g is caused
to oscillate, and the other is caused to remain
55 in a permitting said compartment to empty.
This occurs first on one side and then the
other.

In order to limit the oscillation of the meter,
I also provide the inner edge of the upper seg- 105
60 ment of one of the head-frames B with two
downward-projecting lugs m , which are placed
65 a corresponding distance on either
side of a vertical line intersecting the center
of the meter, and are spaced a distance apart
corresponding to the oscillation of the meter D .
Projecting from the end of the meter between
these lugs is a stud M , which strikes against
toward the lowest part thereof, the radius of
which is greater than the radius of the exterior
of the meter, so as to combine with the outer
walls G placed an equal distance on each
110 side of a vertical line intersecting the center
of the meter, and at such an angle that when
said meter oscillates, the limit of its oscillation
said straight side will lie flat against
the stop-wall, so as to close the opening or
outlet made thereby, as set forth.

2. The case A , having an inlet a and an
outlet b , stop-walls G , and head-frame B , to
which the head-frames B are secured, and which has a cross-bar C and a
115 provided with lugs m^2 , in combination with
an oscillating meter D , the exterior of which
is divided into compartments, the lowest segment
120 thereof, which is slightly greater in diameter and has its ends connected
upon its outer edges to the outer edges of the
trunnions c extending from the ends of the
meter in alignment with its center of oscillation
and journaled in said cross-bars C and
125 lugs m^2 , projecting around the outer end of the
meter near the upper edge thereof, as set forth.

3. The combination, with case A , having
130 inlet a and outlet b , head-frame B , having
cross-bar C from which standards g^2 are
and levers g^3 of the oscillating meter D , vertical
135 partition E , dividing said meter longitudinally, and containing two equal compartments,
each of which has an outlet f and an inlet g , as
described, and the oscillating meter D is attached to the end of the
meter contiguous and with reference to levers
140 g^3 , as and for the purpose set forth.

4. The combination, with case A , having
inlet a and outlet b , head-frame B , having
cross-bar C , from which standards g^2 are
145 and levers g^3 , coil-springs g^4 , and gage-screws k , of
